United States Patent Office

Des. 211,186
Patented May 28, 1968

211,186

PICTURE FRAME

Douglas J. Smith, 57 Heritage Court, Hillsdale, N.J.
07642, and Richard S. Saulsbury, 104-20 Queens
Blvd., Forest Hills, N.Y. 11375

Continuation-in-part of design application Ser. No. 3,654,
Aug. 30, 1966. This application Aug. 21, 1967, Ser.
No. 8,334

Term of patent 14 years

(Cl. D29-20)

FIG. 2.

FIGURE 1 is an exploded view of a two-part picture frame embodying our new design,

FIG. 2 is a perspective view of the assembled frame thereof, and

FIG. 3 is a rear elevational view thereof.

This is a continuation in part of our design patent application, Ser. No. 3,654 filed on Aug. 30, 1966, now abandoned.

We claim:

The ornamental design for a picture frame, substantially as shown and described.
